COMBINATION SOFA OR CHAIR AND
DISAPPEARING TABLEAndrew Yodice and Ann Yodice, Brooklyn, N. Y.
Application July 21, 1948, Serial No. 39,926

4 Claims. (Cl. 155—128)

1

This invention relates to combination articles of furniture, and more particularly aims to provide a novel, useful and practical combination of a sofa or a chair with a table which may readily and quickly be made available in front of the person or persons occupying the chair or sofa and which, when not in use, is entirely concealed within the furniture.

The above broad as well as additional and more specific objects will become apparent in the following description, wherein characters of reference refer to like-numbered parts in the accompanying drawings. It is to be noted that the drawings are intended solely for the purpose of illustration, and that it is neither desired nor intended to limit the invention necessarily to any or all of the exact details of construction shown except insofar as they may be deemed essential to the invention.

Referring briefly to the drawings,

Fig. 1 is a front elevational view of a sofa embodying one form of this invention.

Fig. 2 is a plan view of the same, with parts broken away and partly in section, showing the table in extended position ready for use; it may also be deemed a view on line 2—2, Fig. 3.

Fig. 3 is a side elevational view of the sofa shown in Fig. 2, with parts broken away and partly in section.

Fig. 4 is a fragmentary plan view of the sofa of Fig. 2, showing one of the two table panels in concealed position.

Fig. 5 is a fragmentary plan view of one of the two extensible table panels, with parts broken away and partly in section, together with the swivel connection thereof with the cable by which it is drawn into the side of the sofa, and it may also be considered to be a section on the line 5—5 of Fig. 4.

Fig. 6 is a sectional view taken on the line 6—6 of Fig. 4.

Fig. 7 is a sectional view taken on the line 7—7 of Fig. 5.

Fig. 8 is a sectional view taken on the line 8—8 of Fig. 2.

Fig. 9 is a fragmentary front elevational view of the sofa of Fig. 1, with the table panels, not shown, in extended position ready for use, showing the center support members for the free ends of the panels.

Fig. 10 is a plan view of the center support shown in Fig. 9.

Fig. 11 is a front elevational view of a chair having the same invention applied thereto, in the

2

form of a single panel instead of a double panel as in the case of the sofa.

Referring in detail to the drawings, the numeral 10 indicates a sofa having the hollow back 11 and the hollow sides 12. In each hollow side 12, a pair of horizontally spaced rails 14 are supported in elevated position, as by means of support blocks 13, against the opposed walls 15. A member 16, including a body 18 having spaced parallel hinge ears 19 at one end thereof, is provided on each side of the body with vertically spaced webs 17 which slidably engage the rails 14, as shown in Fig. 6. By means of a pin 21 a projection 20 is pivotally supported between the ears 19. The projection 20 extends from a nut 22 which screws on the threaded end of a stem 23. The latter registers rotatably in a corner of a table panel 24, and is releasably locked therein by a set screw 25 engaging the reduced intermediate portion 26 of the stem. A loop 27 in the end of a cable of flexible wire 28 is loosely engaged in an eyelet 29 in the other end of the body 18.

A hinged door 30 is provided as the front panel of the side 12. It is apparent that when the table panel 24 is in alignment with the vertical plane between the rails 14, the said panel may be slid completely into the side 12. Conversely, when the table panel is withdrawn from the side 12, it may be swung from the vertical to the horizontal position about the pivot 23.

A pulley 31 is provided against the rear wall of the back 11, and a coiled spring 32 is anchored in the back, near the other side 12, at 33. This spring normally tends to draw the panel 24 inward into the side 12, as is obvious.

A second and like table panel 24a is mounted in the same manner in the other (right hand, Fig. 2) side of the sofa, and as all the parts thereof are similar to those above described, they are not shown or described in detail.

When the two table panels 24 and 24a are in positions shown in Figs. 2 and 3, a means is required to hold up the juxtaposed free ends of the panels. Such means is provided in the form of the support 34. A rod 35 is slidably mounted in brackets 36 against the underside of the sofa. Pivotally secured to this rod near the front end, or at the front end, thereof, is a support bar 37, one end 38 of this bar projecting beyond the pivot 35, as shown in Fig. 9, so that when the bar is swung into the vertical position shown the extension 38 reaches the floor 39. The upper end of the bar 37 is provided with spaced ears 40. A pair of similar arms 41 and 42, whose inner ends are arched substantially as shown, are

55

pivots at the extremities of said inner ends, on pins 43, to the ears 40 at opposite ends of the said ears, as more clearly shown in Fig. 10. When folded down into the positions shown in broken lines in Fig. 9, these arms are out of the way, and the bar 37 may be folded down to horizontal position and then the rod 35 is pushed under the couch, into the position shown in Fig. 1. When the arms 41 and 42 are swung, through arcs of approximately 90 degrees from the positions shown in broken lines, Fig. 9, to the positions shown in full lines, they rest on the top edge of the support 37 in horizontal position, and are thus able to support the free ends of the table panels 24 and 24a, as shown.

In the modified form of the invention as applied to a chair, Fig. 11, the same panel 24 is mounted in the side 12a in the same manner as previously described, the hinged door 30a equivalent to the door 38, being provided in the same manner. But one side 12a of the chair is used to house the single table panel 24, and a similar support 37a pivoted to the rod 35a is used in the same manner to hold up the free end of the panel 24.

Obviously, modifications in form and structure may be made without departing from the spirit or scope of the invention.

We claim:

1. In combination, an article of furniture having a seat, a back rising approximately from the floor to a level above the level of said seat, and a hollow side at one end of said seat rising to a level above the level of said seat, said side having two opposed substantially vertical walls, said walls having opposed rails secured thereto near the top thereof, a body having means slidably engaging said rails and thereby being slidably mounted on said rails, a lug pivotally secured to the forward end of said body, a table panel slidably mounted in said hollow side, a stem rotatably mounted in one end of said panel at one corner of the latter, said stem being rigid with said lug, the axis of said stem being at right angles to the pivotal axis between said body and said lug, the front wall of said side having a door therein, said panel thereby when said door is open being extractable from said side and being swingable about said stem into horizontal position, means for supporting the other end of said panel in horizontal position, and means secured to the rear end of said body for normally urging said body and hence also, when said panel is positioned vertically forward of said side, said panel rearward into said side, said back being hollow, said last-named means comprising a coiled spring positioned entirely within said back and having one end anchored in said back, a cable having one end secured to the other end of said spring, a pulley mounted in the chair at the intersection of said hollow side with said hollow back, said cable being trained about said pulley and having the other end thereof secured to said body.

2. In combination, an article of furniture having a seat, a back rising approximately from the floor to a level above the level of said seat, and a hollow side at one end of said seat rising to a level above the level of said seat, said side having two opposed substantially vertical walls, said walls having opposed rails secured thereto near the top thereof, a body having means slidably engaging said rails and thereby being slidably mounted on said rails, a lug pivotally secured to the forward end of said body, a table

panel slidably mounted in said hollow side, a stem rotatably mounted in one end of said panel at one corner of the latter, said stem being rigid with said lug, the axis of said stem being at right angles to the pivotal axis between said body and said lug, the front wall of said side having a door therein, said panel thereby when said door is open being extractable from said side and being swingable about said stem into horizontal position, means for supporting the other end of said panel in horizontal position, and means secured to the rear end of said body for normally urging said body and hence also, when said panel is positioned vertically forward of said side, said panel rearward into said side, said means for supporting the other end of said panel comprising a rod slidably mounted in said article under said seat and adapted to be withdrawn part way therefrom, said rod having a bar pivotally secured to the outer end thereof and thereby being adapted to be swung into vertical position with the upper end thereof positioned under said other end of said panel.

3. In combination, a sofa or like article of furniture including a seat, a back, and hollow sides at the ends of said seat, said back and said hollow sides rising approximately from the floor to levels above the level of said seat, opposed substantially horizontal rails mounted in said hollow sides near the tops of the latter at the same horizontal level, said hollow sides having open front ends, doors on said open front ends adapted to close the same, two universal joints, each of said joints including a body slidably mounted on said rails in one of said sides, two table panels, one end of one of said panels having a corner thereof secured to the forward end of one of said joints, one end of the other of said panels having a corner thereof secured to the other of said joints, means normally urging said bodies rearward in said sides, said panels when in vertical position forward of said hollow sides being adapted to be drawn into said sides by said means, said panels when in said vertical position forward of said hollow sides being swingable into horizontal position with the other ends of the panels juxtaposed, and means for supporting said juxtaposed ends of said panels in said horizontal position, said last-named means comprising a rod slidably mounted on said sofa under said seat and adapted to be pulled part-way outward from the front of said seat, said rod having a bar pivoted to the forward end thereof and being thereby adapted to be swung into upright position, said bar in the latter position having the upper end thereof positioned under and supporting said juxtaposed ends of said panels.

4. In combination, a sofa or like article of furniture including a seat, a back, and hollow sides at the ends of said seat, said back and said hollow sides rising approximately from the floor to levels above the level of said seat, opposed substantially horizontal rails mounted in said hollow sides near the tops of the latter at the same horizontal level, said hollow sides having open front ends, doors on said open front ends adapted to close the same, two universal joints, each of said joints including a body slidably mounted on said rails in one of said sides, two table panels, one end of one of said panels having a corner thereof secured to the forward end of one of said joints, one end of the other of said panels having a corner thereof secured to the other of said joints, means normally urging said bodies rearward in said sides, said panels when

in vertical position forward of said hollow sides being adapted to be drawn into said sides by said means, said panels when in said vertical position forward of said hollow sides being swingable into horizontal position with the other ends of the panels juxtaposed, and means for supporting said juxtaposed ends of said panels in said horizontal position, said last-named means comprising a rod slidably mounted on said sofa under said seat and adapted to be pulled partway outward from the front of said seat, said rod having a bar pivoted to the forward end thereof and being thereby adapted to be swung into upright position, a pair of hook-shaped arms having the extremities of the curved ends thereof pivoted to the top of said rod on opposite sides of the rod and normally lying with the shanks of said arms positioned against said opposite sides of the rod, said rods being swingable upward and in opposite arcuate directions to bring

10
5
20

said shanks to rest on the upper extremity of said rod, said shanks in said latter position extending in opposite horizontal directions with one of said shanks being positioned under one of said panels and the other of said shanks positioned under the other of said panels.
